Des. 216,869
Patented Mar. 17, 1970

216,869

FOOD TRAY OR THE LIKE

Thomas M. Britt, Red Bank, N.J., assignor to Lily-Tulip
Cup Corporation, New York, N.Y., a corporation of
Delaware

Filed June 6, 1969, Ser. No. 17,554

Term of patent 14 years

Int. Cl. D9—04

U.S. Cl. D9—185

FIG. 1

FIG. 2

FIG. 3

FIG. 4

FIG. 5

FIG. 6

FIG. 7

FIGURE 1 is a top view of a food tray, showing my new design;

FIGURE 2 is a front elevational view;

FIGURE 3 is a right side elevational view;

FIGURE 4 is a rear elevational view;

FIGURE 5 is a left side elevational view;

FIGURE 6 is a bottom plan view; and

FIGURE 7 is a cross-sectional view taken along line 7—7 of FIGURE 1.

I claim:

The ornamental design for a food tray or the like, substantially as shown.
